(57) **CLAIM**

The ornamental design for an adjustable golf tee, as shown and described.

DESCRIPTION

FIG. 1 is a perspective view of an adjustable golf tee showing my new design.

FIG. 2 is a front elevation view thereof.

FIG. 3 is an exploded view thereof.

FIG. 4 is a bottom plan view thereof; and,

FIG. 5 is a top plan view thereof.

The broken lines in FIGS. 1-5 are included for the purpose of illustrating portions of the adjustable golf tee that form no part of the claimed design.
